[57] **CLAIM**

The ornamental design for a roller-operable screen for garage door opening, as shown and described.

DESCRIPTION

FIG. 1 is a reduced perspective view of a roller-operable screen for garage door opening, wherein the broken lines show, for illustrative purposes only, a conventional, single-car garage, which garage forms no part of the claimed design;

FIG. 2 is a top plan view of FIG. 1;

FIG. 3 is a front elevational view of FIG. 1;

FIG. 4 is a left side elevational view of FIG. 1;

FIG. 5 is a bottom plan view of FIG. 1; and

FIG. 5 is a bottom plan view of FIG. 1, and FIG. 6 is a rear elevational view of FIG. 1.

FIG. 6 is a rear elevational view of FIG. 1. In the embodiment shown, there is substantial similarity in the corresponding right and left side elevational views, and, as the only difference is the mirror image of one another, only the left side is shown.
